DESIGN FOR A SMOKING PIPE

William T. Clements, Charlotte, N. C.

Application March 12, 1942, Serial No. 106,171

Term of patent 14 years

To all whom it may concern:

Be it known that William T. Clements, a citizen of the United States of America and residing at Charlotte, county of Mecklenburg, State of North Carolina, has invented a new, original, and ornamental Design for a Smoking Pipe, of which the following is a specification, reference being had to the accompanying drawing, forming a part thereof.

Figure 1 is a side sectional view of the smoking pipe showing my design;

Figure 2 is a top plan view of the smoking pipe;

Figure 3 is a bottom plan view of the smoking pipe;

Figure 4 is an end elevational view looking at the right hand end of Figure 1.

I claim:

The ornamental design for a smoking pipe, substantially as shown.

WILLIAM T. CLEMENTS.
